[57] CLAIM

The ornamental design for a gas fired hot water pressure cleaning apparatus, as shown.

DESCRIPTION

FIG. 1 is a front elevational view of the gas fired hot water pressure cleaning apparatus showing my new design;

FIG. 2 is a right side elevational view thereof;

FIG. 3 is a left side elevational view thereof;

FIG. 4 is a rear elevational view thereof; and

FIG. 5 is a top plan view thereof.
